(57) CLAIM

We claim the ornamental design for a chair, as shown and described.

DESCRIPTION

FIG. 1 is a perspective view of a chair.

FIG. 2 is a first side view of the chair of FIG. 1.

FIG. 3 is a second side view of the chair of FIG. 1.

FIG. 4 is a front view of the chair of FIG. 1.

FIG. 5 is a rear view of the chair of FIG. 1; and,

FIG. 6 is a top view of the chair of FIG. 1.

The evenly spaced broken lines illustrate portion of the chair that form no part of the claimed design. The long-short broken lines illustrate a boundary of the claimed design and form no part of the claimed design.

1 Claim, 6 Drawing Sheets
